(57) **CLAIM**

The ornamental design for a upper stub mount elbow style narrowing port hopper body, as shown and described.

DESCRIPTION

FIG. 1 is a top view of a upper stub mount elbow style narrowing port hopper body showing my new design;

FIG. 2 is a back view thereof;

FIG. 3 is a left side view thereof;

FIG. 4 is a front view thereof;

FIG. 5 is a right side view thereof;

FIG. 6 is a bottom view thereof;

FIG. 7 is an isometric view thereof; and,

FIG. 8 is an environmental view thereof showing the hopper body connected to a lid with the broken lines in the drawings used for illustrative purposes only such that the hopper lid forms no part of the claimed design.
